UNITED STATES PATENT OFFICE.

CHARLES L. CHISHOLM, OF MARYSVILLE, NEW BRUNSWICK, CANADA, ASSIGNOR TO
CHISHOLM TRANSMITTER & TELEPHONE INSTRUMENTS COMPANY.

TELEPHONE SYSTEM AND INDIVIDUAL TRANSMITTER THEREFOR.

1,176,522.

Specification of Letters Patent.

Patented Mar. 21, 1916.

Application filed March 21, 1910. Serial No. 550,624.

To all whom it may concern:

Be it known that I, CHARLES LOGAN CHISHOLM, a subject of the King of Great Britain and Ireland, residing at Marysville, in New 5 Brunswick, Dominion of Canada, have invented a new and useful Telephone System and Individual Transmitter Therefor, of which the following is a specification.

This invention has reference to improvements in telephone systems and individual transmitters therefor and its object is to provide a telephone system wherein telephone transmitters may be individual to the users, the transmitter being portable and 10 readily attachable to and detachable from freely accessible circuit terminals of transmitter circuits situated at local stations in the telephone system, which local stations are each provided with a receiver local 15 thereto and may or may not be also provided with a transmitter local to the station.

In ordinary telephone stations of a public or semi-public character there is constant danger of infection of healthy persons with 20 diseases due to the use of the telephones and especially of the transmitters by persons already having diseases. The transmitter is particularly liable to become infected through being used by diseased persons because of the deposition of moisture in the 25 mouth piece of the transmitter and upon the diaphragm during the act of speaking thereto, and disease germs find ready lodgment in the mouth piece already moistened and warmed by use and upon the diaphragm likewise moistened and warmed. The condition for the propagation of disease germs is particularly favorable in the chamber immediately adjacent to the diaphragm of telephone transmitters in ordinary use, and when the moisture has evaporated such germs are readily dislodged and may easily reach the mouth and nose of a subsequent user so that a public or semi-public station 30 is, because of the transmitter, a constant source of danger to users of the telephone.

Various means have been proposed for 35 eliminating the danger of disease infection on the transmitter side of the telephone unit and such means usually consist either of protecting devices for the mouth piece to be removed and destroyed after each use of the telephone, or a constantly present dis-

infectant, or some other like expedient, or an attendant is charged with the duty of 55 cleansing and disinfecting the telephone transmitter after each use.

The removable mouth piece protector is more or less of a nuisance to the user and for this reason the employment of such a 60 protector is often neglected, and furthermore such mouth piece protectors do not prevent the accumulation of disease germs on the diaphragm. If a germ proof shield be employed it interferes with the proper 65 transmission of the sound waves to the diaphragm. The constant presence of a disinfectant is usually highly disagreeable to the user of the telephone. An attendant is often neglectful, and seldom if ever at 70 attempts to cleanse the diaphragm, such diaphragm usually being out of reach.

The desirability of individualizing telephones has long been recognized, both for sanitary reasons and because many persons 75 of refined tastes object to promiscuously used public telephones, but attempts to individualize the telephone have at best only resulted in the production of bulky instruments too large to be readily stored or transported by the ordinary user, and furthermore requiring marked changes in existing 80 telephone installations.

By the present invention the transmitter only is individualized to the user for it is 85 the transmitter that is practically the sole source of danger in the use of public telephones, since the danger from the receiver is almost wholly negligible.

The present invention contemplates not 90 only the features mentioned but other features, resulting in the elimination not only of all the dangers to the health of the users of telephones but of all the disagreeable features of public or semi-public telephones, 95 all of which will be best understood from a consideration of the following detail description taken in connection with the accompanying drawings, in which drawings:—

Figure 1 is a diametric section, with parts in elevation of an individual transmitter as housed in a casing similar to a watch casing, the showing being on a somewhat enlarged scale. Fig. 2 is a view similar to 105 that of Fig. 1 but showing the casing open

and the mouth piece of the transmitter in the operative position. Fig. 3 is a section of the structure of Fig. 1 on a diameter approximately at right angles to the diameter 5 of the section of Fig. 1. Fig. 4 is a view showing the individual transmitter without the protecting casing and with a non-collapsible mouth piece, the latter being shown in section. Fig. 5 is an elevation of a desk 10 set showing the adaptability of the individual transmitter thereto. Fig. 6 is a section, on an enlarged scale of circuit terminals used in connection with the present invention. Fig. 7 is a section, on an enlarged 15 scale, of the terminal carrying portion of the individual transmitter, such terminals being adapted to the local station terminals illustrated in Fig. 6. Fig. 8 is a diagram of a telephone system showing local stations 20 suitably equipped for the use of the individual transmitter. Fig. 9 is an enlarged detail view of a portion of the individual transmitter, with parts in section.

Referring to the drawings and more particularly to Figs. 1, 2 and 3 there is shown a casing 1 provided with a cover 2 which may or may not be hinged to the body of the casing but which is shown in the drawings as so hinged, and the casing with its cover 25 is in size and shape similar to an ordinary watch case, whereby the structure, when closed, is adapted to be placed in the vest pocket if desired, thus making the transmitter highly convenient for individual use. 30 Mounted in the casing 1 is a transmitter element 3 which may be considered as a granular microphonic element of minute size with the diaphragm and granule chamber substantially coextensive, the sound receiving 35 diaphragm being of less diameter than the diameter of the bell end of mouth pieces such as are commonly employed in connection with transmitters. The microphonic element 3 is mounted in the casing 1 between the back thereof and a plate 4 which may overlie in part the diaphragm of the transmitter to form a shallow air chamber. It 40 will be understood however that the plate 4 is not absolutely necessary since the microphonic element may be mounted directly on the inner back wall of the casing 1. Secured to the transmitter element 3 or to the plate 4 where constituting the outer covering 45 for the transmitter element is a mouth piece 5 which may be screwed or otherwise secured to a boss 6 formed on the front of the plate 4 and having a passage therethrough so that 50 sound waves may easily reach the diaphragm in the usual manner.

In order that the transmitter may be readily portable and convenient to the user it is preferred to form the mouth piece 5 in such manner as to be easily collapsible and for this purpose it may be made of a spiral 55 wire 7 having a constant tendency toward

the expanded position but which may be collapsed in the direction of the axis of generation of the spiral, and this spiral wire support 7 is provided with a covering 8 of some suitable flexible material which for 70 the best results should be impervious to moisture. Soft rubber, oiled silk, and like materials are adapted for this purpose.

The mouth piece 5 may remain on the transmitter and when the cover 2 is closed 75 onto the body portion 1 of the casing then this mouth piece will collapse into very shallow space, but by forming the wire 7 of elastic metal, such for instance as piano wire, the mouth piece will have a constant 80 tendency to assume the operative or expanded position. The casing 1 may be provided with a catch 9, push piece 10, and ring 11 similar to like parts in watch cases so that when the cover is closed down on the 85 body portion 1 it will be locked in this position but may be readily released by pressure on the push piece 10 and the cover will then move to the open position either under the action of a spring such as is commonly used 90 in watch cases, or by the expansive impulse of the mouth piece 5. The ring 11 forms a ready means for attaching the casing to a watch chain or other fastening device so that the user may carry the device in the 95 pocket without danger of losing it, in the same manner as a watch is carried. The flexible covering of the spiral wire 7 may either be inside the spiral or outside the 100 same, or the spiral may be housed in such covering.

In the particular structure shown in the drawings there is mounted in the casing 1, between the back of the casing and the plate 4, a block 12 of insulating material having 105 spaced cavities 13 matching spaced openings 14 through the rim of the casing at any convenient point therarround, but preferably located with reference to the push piece 10 in either the six o'clock position or the 110 twelve o'clock position, considering a watch face as usually mounted in a watch casing.

Centralized in the sockets 13 of the block 12 are pins 15 of conducting material and 115 these pins are connected by suitable conductors 16 to the respective electrodes of the microphonic element. The pins 15 therefore constitute the terminals of the microphonic element which terminals are local to the individual transmitter. The terminals 120 15 are preferably within the confines of the casing 1 so that there is no obtrusive projection beyond the casing.

In order to adapt existing telephone systems already installed, or new installations, 125 for the use of the individual transmitters, some modification of such systems is necessary, but where telephone stations are already installed with receivers and transmitters, the transmitters already in place 130

need not be disturbed and provision may be made whereby the individual transmitter may be used, if desired, or the transmitters already installed may be used, each without 5 interference from the other.

A telephone system embodying the present invention is illustrated in Fig. 8, where there is indicated a central station 17 with telephone line conductors 18 extending 10 therefrom to various local stations, two of which latter are indicated as sufficient to illustrate the system of this invention. For convenience of description one of these local stations is designated 19 and the other 20. 15 Each station contains a receiver 21 local thereto. At the station 19 there is installed a transmitter 22 local to this station, and at the station 20 the transmitter itself is omitted but the transmitter circuit is retained. 20 At station 19 the continuity of the transmitter circuit may be readily broken at one point and another circuit established around the transmitter 22 to circuit terminals 23, 24 this new circuit including the 25 primary of the usual induction coil 25 and the charging battery 26 or other charging source for the transmitter circuit at the local station.

In the arrangement shown at station 19 a 30 conductor 27 is branched to the terminal 23 and a conductor 28 is branched to the terminal 24 and when these terminals are bridged, provision is made for cutting out the transmitter 22. A terminal structure 35 adapted for the conditions present at station 19 is illustrated more in detail in Fig. 6, where there is shown a block 29 of insulating material provided with tubular projections or plugs 30 so shaped and spaced as to 40 readily enter the passages 13 in the block 12 of an individual transmitter, the plugs 30 being made elastic by splitting as indicated at 31 or constructed in any other manner to readily lock in the passages 13 without binding therein too firmly to interfere with ready removal of the plugs 30 when desirable. Each plug 30 has a metal tubular lining or sleeve 32 which may be also split to render it elastic and this metal lining 50 32 is designed to receive a corresponding pin 15 constituting a circuit terminal of an individual transmitter. The other end of the sleeve 32 from that entering a plug 30 may receive a metal plug 33 to which may be soldered or otherwise secured the respective conductor 27 or 28 as the case may be. The end of the sleeve 32 within the plug 30 stops short of the outer end of the plug so that accidental contact therewith is prevented. 60

Under the conditions present at local station 19 one of the sleeves 32 is in electrical connection with a plate or strip 34 traversed by the stem 35 of a plug 36 movable 65 in a passage 37 formed in the block 29 in

spaced relation to that plug 30, the conducting sleeve 32 of which is connected to the conducting plate or strip 34. The end of the stem 35 projecting through the plate or strip 34 carries a conducting plate 38 to 70 which there is secured a conductor 39 leading to one side of the transmitter 22. A spring 40 housed within the passage 37 serves to maintain the block 36 in a projected position but this spring will permit the 75 block 35 to move into the passage 37 on the application of sufficient force to compress the spring 39, and this will carry the plate 38 out of contact with the plate 34, but under normal conditions electrical contact is maintained between these two plates. 80

The conductors 28 and 39 constitute portions of the local transmitter circuit at station 19 and this circuit is normally maintained at the plates 34 and 38 by the action 85 of the spring 40 and when the block 36 is undisturbed the telephone transmitter 22 may be utilized in the usual manner. If however, the block 36 be moved against the action of the spring 40 then the telephone 90 transmitter 22 is cut out of the local transmitter circuit.

If in an arrangement such as shown at local station 19 of the system of Fig. 8, an individual transmitter be applied to the terminals 23 and 24 by the introduction of the 95 plugs 30 into the sockets 13, then on the seating of the plugs 30 in said sockets the block 36 is brought into contact with the casing 1 and the spring 39 is compressed 100 thus cutting out the transmitter local to the local station 19 by the act of including the individual transmitter in the transmitter circuit at said station. Under the circumstances assumed it will be seen that either 105 the transmitter local to the station or the individual transmitter may be used as may be desired. This is particularly valuable in semi-public stations where the use of the transmitter there located may be confined 110 to one or more authorized persons while the more general use of the station will be possible for persons supplied with the individual transmitters. By this means the danger of contaminating the transmitter or of 115 transmitting diseases is reduced to a negligible minimum.

Where it is not desirable to have a telephone transmitter as a permanent fixture at the local station, the switching mechanism 120 composed of the block 36 and the plates 34 and 38 is omitted and the telephone transmitter 22 is also omitted, but the local transmitter circuit is retained together with the readily accessible terminals 23 and 24 adapted 125 to be inserted in the sockets 13 to complete the circuit to the individual transmitter microphonic element through the pins 15. This arrangement is shown at station 20 in Fig. 8. At this local station 20 the conduc- 130

tors 27 and 28 are indicated as forming a flexible cord, and it will be understood that a flexible cord may or may not be used as desired, at any or all the stations.

In Fig. 5 there is shown a desk set 41 having readily accessible circuit terminals 23-24 in the transmitter circuit, and an individual transmitter 1 may be readily applied to or removed from these circuit terminals at will and without the aid of tools, this facility of attachment to and removal of the individual transmitter from the readily accessible terminals in the transmitter circuit at the local stations, whatever type of telephone unit be used together with the ready portability of the individual transmitter and its unobtrusive size whereby it is adapted to small pockets such as vest pockets, greatly enhances the usefulness of the individual transmitters.

Where the collapsibility of the mouth piece 5 is not of prime importance, a non-collapsible mouth piece 42, shown in Fig. 4, may be applied to the transmitter 3 and the latter may replace the transmitter 22 of station 19 or may be used as an individual transmitter to be removed from the readily accessible transmitter circuit terminals and stored away when not in use to prevent others than the owner of the particular instrument from using the same. In order to provide for the ready cleansing of the diaphragm of the individual transmitter the portion of the plate 4 immediately overlying the diaphragm is in the form of a readily removable screw plug 43 shown in Fig. 9.

It will be understood that the arrangement of circuit terminals described is indicative only, and the showing of the drawings does not preclude the use of other circuit terminals and other means for connecting the individual telephone transmitter into a telephone system, whether the local transmitter be present or not, this coupling of the individual transmitter into the circuit being possible without the aid of tools and at will.

The individual transmitter being of small size and of few parts is readily manufactured at small cost and may be sold profitably at a very moderate price.

One of the principal advantages of the individual transmitter is due to its being strictly sanitary and thereby preventing the establishing of centers of infection and the spread of disease, for the use of the transmitter is confined to one individual.

The invention is particularly useful in connection with telephones installed in hospitals or hotels or public telephone booths or any other public or semi-public place. Persons afflicted with diseases liable to be transmitted can with the individual transmitter readily use telephones and have the satisfaction of knowing that such use is free from the liability of endangering others.

The extreme cleanliness of the individual transmitters will present a welcome relief to those who object from cleanly motives to the miscellaneous use of telephones. There is also another advantage of the individual transmitter which however is commercial rather than sanitary. By the employment of the individual transmitter the indiscriminate use of the telephone by non-subscribers is prevented since telephone systems installed for use with the individual transmitter only could not be used by others and the very purpose for which the individual transmitter is provided would prevent its being loaned by the owner to others.

While the particular construction of the microphonic side of the individual transmitter, of this invention does not enter into the present invention, it may be stated that the transmitter, including the sound receiving diaphragm and the granule chamber, may be less than one inch in diameter and less than three sixteenths of an inch in thickness and the casing inclosing the transmitter need only be sufficiently large to accommodate the mouth piece when in the collapsed condition and since the open end of such mouth piece has been found in practice to operate successfully when of less diameter than the mouth pieces in common use, the entire structure need not exceed the size of a medium size watch of thin model.

What is claimed is:

1. A telephone system having stations with telephone receivers and telephone transmitters local to said stations, the local circuits of said transmitters being each provided with normally accessible circuit terminals bridging the local transmitters, individual telephone transmitters having circuit terminals adapted to be applied to and removed from the normally accessible circuit terminals of the transmitter circuits at the local stations, and means for the electrical elimination of the local telephone transmitters from the local transmitter circuits on the inclusion of the individual transmitter in the local telephone transmitter circuit.

2. A telephone system comprising telephone units at local stations and each provided with circuit terminals for the transmitter circuit in addition to the transmitters included in the telephone unit, a switch in the local telephone transmitter circuit movable to electrically eliminate the local transmitter, and an individual telephone transmitter includable in and removable from the local transmitter circuit at will and without the aid of tools.

3. In a telephone system, a telephone station having a transmitter and a receiver both local to said station, a telephone transmitter includable in and removable from the local transmitter circuit at will and without the aid of tools, and means for electrically

eliminating the local transmitter when the second named transmitter is included in the local transmitter circuit.

4. In a telephone system, a telephone station having a transmitter and a receiver both local to said station, a telephone transmitter includable in and removable from the local transmitter circuit, and means for electrically eliminating the local transmitter when 5 the second transmitter is included in the local transmitter circuit comprising a switch in the first transmitter circuit responsive to the inclusion of the second transmitter in the transmitter circuit to break 10 the circuit to said first named transmitter.
5. In a telephone system, a telephone station having a transmitter and a receiver both local to said station, the transmitter being included in a circuit provided with accessible circuit terminals, and a switch associated with said circuit terminals, and a telephone transmitter with circuit terminals matching those at the telephone station and engaging the switch to open the same on 20 the application of the transmitter carried terminals to the accessible terminals at the 25 station.
6. In a telephone system, a telephone station having a transmitter and a receiver, and suitable circuits local to said station, circuit terminals included in the transmitter circuit, a switch also included in the transmitter circuit and having a normal tendency to the closed position, said switch 30 being associated with the circuit terminals, and a telephone transmitter having circuit terminals matching the circuit terminals with which the switch is associated and adapted to be connected to and removed 35 from the local transmitter circuit terminals at will and without the aid of tools, the switch in the local transmitter circuit responding to the inclusion of the second named transmitter in said circuit to open 40 the circuit to the first named transmitter.
- 45

7. A telephone system comprising a telephone set at a local station, an individual transmitter includable in and removable from the transmitter circuit at the local station at will and without the aid of tools, and 50 means for rendering the transmitter at the local station inactive while the individual transmitter is included in the transmitter circuit at such station.

8. A telephone system comprising a telephone set at a local station, an individual transmitter includable in and removable from the transmitter circuit at the local station at will and without the aid of tools, and means for rendering the transmitter at 55 the local station inactive while the individual transmitter is included in the transmitter circuit at such station and restoring the local transmitter into active relation to the transmitter circuit when the individual 60 transmitter is removed from said transmitter circuit.

9. A telephone system comprising a telephone set at a local station, an individual transmitter includable in and removable 70 from the transmitter circuit at the local station at will and without the aid of tools, and means for rendering the transmitter at the local station inactive while the individual transmitter is included in the transmitter circuit at such station and restoring the local transmitter into active relation to the transmitter circuit when the individual 75 transmitter is removed from said transmitter circuit, said means responding automatically to the inclusion in and removal of the individual transmitter from the transmitter circuit.

In testimony that I claim the foregoing as my own, I have hereto affixed my signature in the presence of two witnesses.

CHARLES L. CHISHOLM.
